STRONG BOX

Charles F. Meilink and Kenneth C. Weatherby,
Toledo, Ohio, assignors to the Meilink Steel
Safe Company, Toledo, Ohio, a Corporation of
Ohio

Application May 7, 1931. Serial No. 535,590

5 Claims. (Cl. 109—1)

This invention relates to safes and the loading thereof.

This invention has utility when incorporated in vestibule-providing money safes, especially when 5 loaded with a protecting weighted mass.

Referring to the drawings:

Fig. 1 is a front view of an embodiment of the invention in a strong box having advantages in installation and use at service stations, filling 10 stations for automobiles and chain store types of retail establishments;

Fig. 2 is a section on the line II—II, Fig. 1;

Fig. 3 is a section on the line III—III, Fig. 1;

Fig. 4 is a partial section on the line IV—IV, 15 Fig. 3;

Fig. 5 is a vertical section through the loading shell having a strong box therein and ready to receive the cement;

Fig. 6 is a plan view of the structure of Fig. 5, 20 with the cover removed;

Fig. 7 is a bottom plan view of the cover, and Fig. 8 is a section on the line VIII—VIII, Fig. 6.

For store fixture assembly in symmetry with counter 1, loading mass of reinforced concrete 25 2 may have its top 3 approximate continuity with the height of the counter. Embedded in the mass 2 is unit 3, which may be a casting of manganese steel, or other effective attack-resisting material.

This unit 3 has drop portion to closed lower 30 end 4 from which rises inclined bottom 5 of inner chamber 6 having parallel side walls 7, 8, connected by back wall 9 rising from the end 4. Opposing the back wall 9 is door frame 10 providing a threshold to the inner chamber 6. Hinge 11 35 mounts circular door 12 in the frame 10. In closed position of the door 12, lug 13 is in clearance region 14 back of the frame 10, and door-locking bolt 15 is in clearance region 16. This door 12 is provided with lock 17.

40 This door 12 closes off the inner chamber 6 from vestibule 18, except as to port 19 in the door frame 10 above the door 12. This port 19 extends horizontally and directs coin or other loaded envelopes for stacking in order as thrust there-through to fall upon the chute 5.

The vestibule 18 is an outer chamber provided with circular opening 20. Hinges 21 mount door 22 to swing into closing position at the opening 20 to be there held closed by lock having outwardly projecting operating spindle 23. This spindle 23, centrally of the door 22, is operable to thrust bolt means 24 back of overhang 25 in locking the door 22 in closed position. Axis 26 of the closed door 22 is eccentric to axis 27 of the closed door 55 12. There is thus clearance for the inner door

portion remote from the hinge to swing into a portion of the opening 20.

Fortification of the strong box proper is had by the design of the loading or weighting mass 2. This concrete is specially selected and mixed for producing a hard as well as heavy body to resist force. Reinforcing rods 28 spaced along sustaining bar 29 may be wired or spot weld anchored in such assembly for the instance when the structure is shipped without the concrete. The casting 60 of the concrete therein may then occur, even at the location for use installation. The shell for the body of concrete may be a metal envelop, further contributing strength over a naked concrete casting. 65

The shell is shown provided with a peripherally flanged bottom 30 in which is set sheet metal unit having rear wall 31 and pair of forwardly extending side walls 32. Between the free ends of the walls 32 a front section 33 is located with its 70 countersink or throat 34. The side walls 32 are stiffened by inner channels 35 extending upwardly from the bottom plate 30. The rear wall 31 is stiffened by angle 36 medially thereof and extending upwardly from the bottom 30. 75

Across the inside of the front section 33 is angle 37 just below the throat 34. From this angle 37 central portion there extends rearwardly angle 38 to the angle 36. In the instance that the strong box proper has a drop rear section, the 80 angle 38 is given an inclined direction to conform thereto. This angle 38 thus serves as a strut which also anchors and sustains the strong box in the structure when shipment is had without a loading thereof with cement. The drop 85 bottom inner chamber is a factor contributing to capacity for the strong box with a minimum of floor space required for the box pedestal. The bar 38 when embedded in the cement is a reinforcement, and it also serves to hold the box in 90 proper position in the shell for the casting of the cement thereabout. These metal parts of the shell, together with the angles and channels are anchored in set up position by welds. 95

The strong box may be introduced through the 100 throat 34 and welded in position with the reinforcements thereabout. The overhang about the throat 34 is beyond the spindle 23 and the hinge 21, and is a protection against jamming should the structure be overturned. Furthermore this 105 countersink about the entrance to the strong box renders such less accessible to forcible attacks. Bar 39 between the channels 35 and over the box is supplementary holding means for the strong box. 110

Cover 40 with peripheral flange 41 may be slipped downward upon the freshly poured concrete filling the shell to have prongs 43, which are spot welded to depend from the under side thereof, embed for setting and anchoring in the concrete. This may provide sufficient anchorage for the cover. However, when such capping occurs at the place of manufacture for the safe, welds may anchor the cover flange 41 to the shell section 33 and the sides 31, 32.

Strong box 43 is shown of sheet metal, instead of a casting as the unit 3, but even such is substantial herein for a high protective rating. The outer chamber or vestibule may be the only one to which the depositor has access. Such depositor, as the retail clerk or branch store manager, may place the small allotment of loose change in the vestibule for his removal upon occasion. Regulations may be effective for controlling accumulations to be placed in envelopes and deposited through the port 19. The system may involve identity for the value of the separate envelopes and to be identified by coupons in series. The traveling auditor or collector may check directly from the depositor's stub book and verify by the collected envelopes which such collector may abstract from the strong box inner chamber. This checking is readily done, for the configuration of the box with the chute side retains such envelopes in the order of their deposit.

The mass of the load 2 safeguards the strong box against ready portability. The mass as built up on its pedestal to counter height, may thus provide a support for a cash register or be given other use for maximum trading economy of the store room. The armoring of the reinforced concrete is substantial, and the shell is a further factor of strength against attack and any unauthorized access to the strong box.

What is claimed and it is desired to secure by Letters Patent is:

1. For a safe adapted to be assembled in a protective housing, said safe having an inner vertical wall having a port, and an inner chamber having a chamber bottom inclined downward away from the port into the housing.

2. A safe comprising a strong box having a door, a concrete mass enveloping the box and having an opening for the door in the side of the mass upwardly from the mid portion thereof for the mass to provide a pedestal therebelow, and reinforcing rods embedded in the mass over the box and extending downward therefrom into the pedestal.

3. A safe comprising a strong box, and a metal shell therefor including peripherally flanged top and bottom sections, an intermediate section over which the top and bottom sections telescope, there being continuous to the strong box a countersink throat shell portion in the intermediate section nearer the top than the bottom section of the shell with the shell sections therebelow forming a pedestal, said throat providing an entrance way to the strong box housed in the shell, and a loading reinforcement in the shell about the strong box positioning the box as to the shell.

4. A safe shell having inner opposite reinforcing channels, a tie bar between the channels, and a strong box anchored to the tie bar to be thereby spaced from the shell.

5. A safe shell having a lateral entrance, a reinforcing bar below the entrance and spaced from the bottom of the shell, a reinforcing bar rearwardly of the entrance and upwardly extending from the shell bottom, a strut extending between the bars, and a strong box located in the entrance and on the strut.

CHAS. F. MEILINK.
